DESIGN FOR A SCREW MACHINE

William E. Joyce, William H. Himes, and Delbert I. Wilson, Dayton, Ohio, assignors to The City Engineering Company, Dayton, Ohio, a corporation of Ohio

Application January 12, 1942, Serial No. 105,120

Term of patent 7 years

To all whom it may concern:

Be it known that we, William E. Joyce, William H. Himes, and Delbert I. Wilson, citizens of the United States, residing at Dayton, in the county of Montgomery and State of Ohio, have invented a new, original, and ornamental Design for a Screw Machine, of which the following is a specification, reference being had to the accompanying drawings, forming a part thereof, wherein:

Figure 1 is a front perspective view of a screw machine illustrating our new design;

Figure 2 is a top plan view thereof, with the ends of the mechanism portions broken away for convenience of illustration.

Figure 3 is a left end view thereof;

Figure 4 is a right end view thereof.

We claim:

The ornamental design for a screw machine, substantially as shown.

WILLIAM E. JOYCE.

WILLIAM H. HIMES.

DELBERT I. WILSON.
